WORK HOLDER FOR GRINDERS

Charles Ira Lott, Lansing, Mich.

Application November 23, 1933, Serial No. 699,442

7 Claims. (Cl. 51—103)

- The invention relates to work holders for grinders, and has for its object to provide a device of this character comprising an elongated member having one or a plurality of apertures extending entirely through the same and adapted to receive therein one or more barrel-shaped bearing rollers to be finished by passing the bar through rollers, which rollers revolve the bearing rollers for grinding the peripheral faces thereof.
- 10 A further object is to provide concave opposite walls in the apertures of the elongated member conforming with the shape of the sides of the rollers to be held therein for ensuring against transverse displacement of the rollers in the apertures during their rotation and with their opposite convex sides projecting beyond the opposite sides of the elongated member where they can be engaged by turning and grinding wheels when passed between said wheels.
- 15 20 A further object is to form the elongated members from hingedly connected sections having registering recesses forming the roller receiving apertures, and when open allowing insertion of the bearing rollers.
- 25 A further object is to provide means whereby one of the holder sections may move longitudinally in relation to the other holder section, thereby allowing the sections to accommodate themselves to proper registration on opposite ends of the bearing elements held therein, according to the shape of the bearing.
- 30 A further object is to provide means for holding the holder sections in closed position at their free ends.
- 35 With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.
- 40 In the drawing:
- 45 Fig. 1 is a perspective view of the work holder showing a plurality of barrel bearing members therein;
- 50 Fig. 2 is a side elevation of the holder;
- 55 Fig. 3 is a top plan view of the holder showing the same in position to be passed between a rotating guide roller and a grinding wheel;
- Fig. 4 is a detail perspective view of a portion of one of the hinged bar members; and
- Fig. 5 is a vertical transverse sectional view through the carrier bar, showing the same in
- position between the rotating roller and the grinder wheel.
- Referring to the drawing, the roller holder comprises elongated sections 1 and 2, which sections are preferably hingedly connected together at 3 through an elongated slot 4 whereby the sections may move slightly longitudinally in relation to each other to accommodate themselves to the rollers 5 disposed therein, and which rollers are preferably of the barrel type as shown. It is to be understood that the holder can be utilized for cylindrical rollers if desired, and applicant does not limit himself in this particular. The loose connection formed by the pin 3 and elongated aperture 4 will allow proper reception of the ends of the barrel-shaped bearing members 5, as the sections 1 and 2 are swung together towards closed position as clearly shown in Figs. 1 and 2. Although it is not absolutely essential to provide fastening means between the sections 1 and 2 at their free ends, as the sections, incident to their weight and horizontal movement over the grinder table 6, would remain closed, they are preferably provided with a spring fastener 7 at their free ends for preventing accidental opening of the holder while handling.
- The holder sections 1 and 2 are provided with recesses 8 which register when the sections are in closed position, as shown in Fig. 2, and the sections when closed bring the recesses 8 into registration so that they conform to the shape transversely of the rollers 5 and receive opposite sides of the rollers in the recesses 8, which are concave and conform to the peripheral contour of the rollers, thereby preventing transverse displacement of the rollers in the apertures of the bars 1 and 2.
- It will be noted that the carrier bar as a whole is narrower than the diameter of the bearing rollers 5, therefore said bearing rollers will extend beyond the opposite sides of the bar so that their peripheries will engage the roller rotating wheel 11 which preferably rotates in the direction of the arrow *a* for rotating the rollers 5 in the opposite direction to the direction of rotation of the grinder wheel 10, located on the opposite side of the holder, and which grinder wheel is transversely curved as well as circumferentially channelled to conform to the desired curvature of the rollers. It is to be understood that the rollers are first made substantially to dimensions and that the grinding operation finishes and polishes them to dimensions. It will be noted that as the bars are passed between the grinding and turning wheels 10 and 11, the rollers will be finished and polished.

as they are progressively placed in engagement with the wheel by the operator. Although a limited number of rollers are shown in the holder, any number may be placed therein, and the holder 5 may be of any length desired.

From the above it will be seen that a bearing roller holder is provided for holding the rollers while rotating and grinding, and said device is simple in construction, the parts reduced to a 10 minimum, and said rollers are held rotatably in the holder by engagement with concave walls within the holder, thereby obviating other holding means and allowing opposite sides of the rollers to project beyond the sides of the holder into 15 the path of rotatable wheels of a finishing machine.

The invention having been set forth, what is claimed as new and useful is:—

1. A device for holding barrel-shaped rollers 20 during grinding of the convex sides comprising a bar of less thickness than the smallest diameter of the rollers, said bar being formed with a recess having sides conforming in shape to the convex sides of the rollers, the axis of said recess 25 extending transverse to the axis of the bar whereby the entire length of the convex sides of the rollers are accessible for grinding.

2. A device for holding barrel-shaped bearing 30 rollers during grinding of the convex sides comprising a longitudinally movable member having roller receiving seats therein extending entirely therethrough and having sides conforming in shape to the convex sides of the rollers, the axis of said seats extending transverse to the axis of 35 the bar, said seats being positioned so that the entire length of the sides of the rollers extend beyond the sides of said member and are accessible for the grinding.

3. A device for holding barrel-shaped bearing 40 rollers during grinding of the convex sides comprising a longitudinally movable member having roller receiving seats therein extending entirely therethrough and having sides conforming in shape to the convex sides of the rollers, the axis of 45 said seats extending transverse to the axis of the bar, said longitudinal member being narrower than the diameter of the rollers, whereby the sides of the rollers extend beyond the sides of said member and are accessible for the grinding.

50 4. A device for holding barrel-shaped bearing rollers during grinding of the convex sides thereof comprising a longitudinally movable member having roller receiving recesses extending entirely through the same, said recesses having concave

walls conforming to the shape of the side walls of the rollers, the axes of said recesses extending transversely of the member, said member being narrower than the rollers, whereby opposite sides of the rollers in said recesses extend beyond opposite sides of the member and are accessible for grinding. 5

5. A device for holding barrel-shaped bearing rollers during grinding of the convex sides thereof comprising a longitudinally movable member 10 having roller receiving recesses extending entirely through the same, said recesses having concave walls conforming to the shape of the side walls of the rollers, the axes of said recesses extending transversely of the member, said member being 15 narrower than the smallest diameter of the rollers, whereby opposite sides of the rollers in said recesses extend beyond opposite sides of the member and are accessible for grinding. 15

6. In a device for holding barrel-shaped bearing rollers during grinding of the convex sides thereof, a work-holding magazine comprising a longitudinally movable member having roller receiving apertures extending entirely through the same, said apertures having concaved walls 20 conforming to the shape of the sides of rollers, the axes of said apertures extending transversely of the member and cooperating with opposite sides of rollers for rotatably holding the rollers in the apertures, the thickness of said member being 25 less than the smallest diameter of the rollers whereby opposite sides of said rollers are simultaneously accessible for grinding, said member being formed from registering sections having 30 portions of the roller apertures therein. 35

7. In a device for holding barrel-shaped bearing rollers during grinding of the convex sides thereof, a work-holding magazine comprising an elongated longitudinally movable member having roller receiving apertures therein, the axes of said 40 apertures extending transversely of said member, means for holding rollers rotatably within the apertures with the entire extent of their opposite sides of the rollers extending beyond opposite sides of the longitudinally movable member whereby opposite sides of said rollers are accessible, said longitudinally movable member being formed from hingedly connected sections having recesses therein which register when the sections 45 are in closed position for forming the roller receiving apertures and receiving the ends of the rollers. 50
